PLATE GLASS SURFACING TABLE

William Owen, Pittsburgh, Pa., assignor to Pittsburgh Plate Glass Company, Allegheny County, Pa., a corporation of Pennsylvania

Application March 29, 1938, Serial No. 198,674

3 Claims. (Cl. 51—240)

The invention relates to tables for use in surfacing plate glass, in which the tables are passed in a continuous train beneath a series of grinding and polishing runners. The heat developed in the polishing operation causes the tops of the tables to warp or bow slightly, so that they are no longer true and flat, and when returned to the grinding end of the cycle for reuse, this bowed or warped condition persists to a certain extent, so that the glass sheets are not ground to uniform thickness, the sheets being ground thinner in the portions overlying the centers of the tables than those overlying the sides of the tables. The object of the present invention is to provide an improved table construction, in which the warping of the table tops due to the heat developed in polishing is substantially eliminated. Briefly stated, this is accomplished by employing a table of ordinary construction, but provided with a false top with a space beneath supplied with a cooling fluid, fins being provided on the lower side of the false top to promote the rapid conduction of heat from such top to the fluid. The cooling fluid may be circulated through the space between the two tops, while the table is passing beneath the polishing section of the surfacing system, or such space may merely be filled with the fluid, such as water, when the table starts past the polishing section, followed by a removal thereof at the end of such section. Certain embodiments of the invention are illustrated in the drawings, wherein:

Figure 1 is a plan view of a part of the table. Fig. 2 is a transverse section on the line II—II of Fig. 1. Fig. 3 is an enlarged section on the line III—III of Fig. 1. And Figs. 4, 5 and 6 are views similar to Figs. 1, 2 and 3, but showing a modification.

Referring to the drawings, the table comprises a body portion consisting of the top 7 reinforced by the ribs 8 and 9, the wheels 10a suitably attached to the body portion and riding upon the rails 16. Seated upon the top 7, but spaced away therefrom is a false top comprising the plate 11 which is provided on its lower side with the series of fins or ribs 12, the plate 11 being preferably a casting with the ribs integral therewith. These ribs are of tapering shape, as indicated in Fig. 3, and their lower ends, which are all machined to the same plane, rest upon the top 7. The plate 11 is clamped securely to the top 7 by means of a plurality of clamping bolts 14 distributed over the area of the table and screwed into lugs 15 which are also integral with the plate 11. This provides a very rigid support for the false top 11 carrying

the glass sheet to be surfaced. A sheet 12a of insulating material, such as vulcanite or Bakelite, may be employed to further retard a transfer of heat to the plate 11.

In order to provide for the cooling of the false top 11, so that it will not warp during the polishing operation, provision is made for circulating a cooling fluid through the space 16 during the period in which the tables are passing beneath the polishing section of the surfacing apparatus. This result is accomplished by the use of a plurality of nozzles 17 arranged along the line of travel of the tables. The cooling fluid may be either compressed air or water. The circulation of this fluid through the space 16 prevents the top 11 from being heated, so that it will warp, and the heat is also conducted away from the plate 11 to such an extent that the temperature change is relatively low and warping is avoided in this plate. The use of the fins 12 not only provides for very secure support of the plate 11, so that all parts thereof will remain in a true plane, but also provides for the rapid transfer of heat from the plate 11 to the cooling fluid which is passing through the space 16. The plate 11 is, therefore, maintained at a much lower temperature than would be possible if the radiating fins 12 were not employed. Due to the stiffening effect of the fins, it is also possible to make the plate 11 of less thickness than would otherwise be the case, so that the heat conduction through the plate is increased, and there is less tendency to warp because of its relatively lower temperature.

Figs. 4 to 6 illustrate a modification which differs from that of Figs. 1 to 3, only in the method of cooling the space between the plates 7 and 11 and in the detail that the fins 18 extend longitudinally of the table instead of transversely thereof. The space between the two plates is in this case closed by the flanges 19, 19, so that a closed space is provided, instead of one having openings at its edges, as is the case in the first form of construction. Means are provided for filling the space between the plates in the form of a pipe 20 which leads to the side of the table 45 and is provided with a hose connection 21. When the table reaches the polishing section of the system, a water supply connection is attached at 21 and the space between the plates 7 and 11 is filled with water. This supply of water is maintained in the cooling space until the table passes the polishing section, at which time, it is drained out through the connection 21 or through some other suitable outlet. In order to permit the space between the plates to fill up completely, an 55

air vent 22 is provided. When the space is completely filled with water, this vent is closed by screwing in the vent plug 23. In this construction, as in that of Figs. 1 to 3, the use of the fins 18 provides for the rapid transfer of heat from the false top 11 to the body of water there beneath, so that the top 11 is heated during the polishing operation to a much lower temperature than would otherwise be the case and any warping incident to the heating of the plate is, therefore, reduced.

What I claim is:

1. A plate glass surfacing table comprising a metal body portion with a flat upper face, a false top comprising a metal plate having a flat upper surface in parallel with said face for receiving the glass to be surfaced, and having on its lower side distributed thereover, a plurality of elongated fins integral with the plate with their ends in opposition to the upper face of the body portion and acting as spacers, means for clamping the false top against the face of the body portion, and means for supplying a cooling fluid to the space beneath the false top.
2. A plate glass surfacing table comprising a metal body portion with a flat upper face, a false top comprising a metal plate having a flat upper

surface in parallel with said face for receiving the glass to be surfaced, and having on its lower side distributed thereover, a plurality of elongated fins integral with the plate with their ends in opposition to the upper face of the body portion and acting as spacers, means for clamping the false top against the face of the body portion, and means for supplying a cooling fluid to the space beneath the false top, said fins tapering in cross section from their upper to their lower ends.

3. A plate glass surfacing table comprising a metal body portion with a flat upper face, a false top comprising a metal plate having a flat upper surface in parallel with said face for receiving the glass to be surfaced, and having on its lower side distributed thereover, a plurality of elongated fins integral with the plate with their ends in opposition to the upper face of the body portion and acting as spacers, means for clamping the false top against the face of the body portion, and means for circulating a cooling fluid through the space between the upper surface of the body portion and the false top.

WILLIAM OWEN. 2
